(57) **CLAIM**

The ornamental design for a pet comb and cover set, as shown and described.

DESCRIPTION

FIG. 1 is a front, left and bottom perspective view of the pet comb and cover set in a combined state, showing my new design;

FIG. 2 is a front, left and bottom perspective view of the pet comb and cover set shown with the pet comb separated from the cover;

FIG. 3 is a front, left and bottom perspective view of the cover without the pet comb, to show aspects of the design that are not visible when shown in a combined state;

FIG. 4 is a rear, right and top perspective view thereof;

FIG. 5 is a front view thereof;

FIG. 6 is a rear view thereof;

FIG. 7 is a left side view thereof;

FIG. 8 is a right side view thereof;

FIG. 9 is a top plan view thereof;

FIG. 10 is a bottom plan view thereof;

FIG. 11 is a front, left and bottom perspective view of the pet comb without the cover, to show aspects of the design that are not visible when shown in a combined state;

FIG. 12 is a rear, right and top perspective view thereof;

FIG. 13 is a front view thereof;

FIG. 14 is a rear view thereof;

FIG. 15 is a left side view thereof;

FIG. 16 is a right side view thereof;

FIG. 17 is a top plan view thereof; and,

FIG. 18 is a bottom plan view thereof.

The claim is directed to the collective appearance of the pet comb and cover set.

The broken lines shown in the drawings illustrate portions of the pet comb and cover set that form no part of the claimed design.
